UNITED STATES PATENT OFFICE.

JAMES SHAW, OF PATERSON, NEW JERSEY.

SHUTTLE.

Application filed December 18, 1924. Serial No. 756,805.

To all whom it may concern:

Be it known that I, JAMES SHAW, a citizen of the United States, and a resident of Paterson, in the county of Passaic and State 5 of New Jersey, have invented a new and Improved Shuttle, of which the following is a full, clear, and exact description.

This invention relates to a shuttle. In most shuttles now in use there is a recess 10 at one end in which a tensioning device is disposed. In this recess a plurality of pins are located which are usually mounted therein by boring holes through the body of the shuttle and fastening the pins therein. 15 These pins are generally not rotatable and in due time become worn by the thread which is constantly rubbing thereagainst. When they are worn or broken by the thread they have to be removed, and in removing 20 them the holes in which they are mounted have to be slightly enlarged. When new pins are put in these holes they have to be sealed therein and oftentimes the sealing material gets loose and the pins drop out, 25 causing the imperfect operation of the shuttle and also sometimes considerable damage to the warp thread. Furthermore, to repair a warp thus damaged requires considerable time and expense to replace the great number 30 of threads broken out.

It is the main object of my invention to provide a means within the recess at one end of the shuttle for mounting the pins that are used in conjunction with the tensioning 35 device, this mounting being in the form of a box which can be very readily inserted into the recess and removed therefrom.

Another object concerns the provision of 40 simple and efficient means whereby the pins are loosely mounted in the box and can rotate, so that the wear on them due to the rubbing of the thread is considerably reduced.

A further object concerns the provision of 45 simple and efficient means whereby the pin box is very easily inserted in the recess and is held therein by a single screw, this screw also serving as a pivot pin for the tensioning device as well.

50 The invention is illustrated in the drawings, of which—

Figure 1 is a partial elevation of one end of the shuttle;

Fig. 2 is a plan view;

55 Fig. 3 is a section taken on the line 3—3 of Fig. 1;

Fig. 4 is a section taken on the line 4—4 of Fig. 3;

Fig. 5 is a perspective view of the pin box; and

Fig. 6 is a section taken on the line 6—6 of Fig. 5.

The form of the invention shown in the drawings is a preferred form, although it is understood that modifications in the construction and arrangement of the parts and in the character of the materials used may be adopted without departing from the spirit of the invention as set forth in the appended claims.

The preferred form of the invention is applicable to a shuttle 1 having a recess 2 in one end thereof. Through this recess a filler thread 3 is adapted to extend. This thread generally comes in contact with a plurality of stationary pins, such as 4, and also in contact with a plurality of eyes 5 mounted on an arm 6 pivoted on a screw 7, this arm and the eyes forming a tensioning device for the filler thread. One end 8 of the arm is connected to a resilient member 9 which is fastened at a fixed point 10, so that the resilient member will hold the arm 6 in a definite normal position. It is the mounting of the stationary pins 4

that has hitherto caused trouble in the operation of shuttles, and the expenditure of time and labor to replace them when broken or when they have become lost. However, I provide a box formed of two parallel 90 plates 11 and 12 of metal, preferably connected to an end wall 13 which has a tit or projection 14 thereon. These plates are provided with suitable aligning apertures in which the pins 4 are disposed, the apertures being slightly larger than the diameter of the pin so that the pins can rotate therein and can be readily inserted. This box is covered by a similarly shaped casing 15 of 95 very thin metal, merely for the purpose of preventing the pins from dropping out of the box.

The box and this thin sheet of metal are provided with aligning apertures 16 through which the screw 7 extends, this screw being 100 disposed at its opposite ends in the body of the shuttle. The tit 14 projects into a notch formed in the front wall of the recess 2.

It is obvious, therefore, to insert the pin box into the recess 2 it is merely necessary to insert it, whereby, first, the tit 14 enters

its notch and the apertures 16 are aligned with the holes in the shuttle body so that the screw 7 may be introduced into place, this screw also acting as a pivot pin for the 5 tensioning device 6.

In this manner, therefore, if any of the pins should become worn, it is merely necessary to remove the screw 7 whereupon the entire box can be slipped out of the recess, 10 then by merely removing the thin sheet or casing 16 the pins will drop right out of the box and can be replaced readily by new pins.

What I claim is:—

16 1. In a shuttle having a recess, a removable pin box disposed therein, said pin box comprising a pair of spaced connecting plates having aligning apertures, a plurality of pins loosely disposed in said apertures, and a thin casing adapted to be slipped over the box, and conforming in shape thereto, for the purpose of holding the pins in place.

2. In a shuttle having a recess, a removable pin box disposed therein, said pin box comprising a pair of spaced connecting

plates having aligning apertures, a plurality of pins loosely disposed in said apertures, and a thin casing adapted to be slipped over the box, and conforming in shape thereto, for the purpose of holding the pins in place, said box having a tip projecting therefrom to engage in the notch in said recess.

3. In a shuttle having a recess, a removable pin box disposed therein, said pin box comprising a pair of spaced connecting plates having aligning apertures, a plurality of pins loosely disposed in said apertures, a thin casing adapted to be slipped over the box, and conforming in shape thereto, for the purpose of holding the pins in place, said box having a tip projecting therefrom to engage in the notch in said recess, said casing and box having aligning apertures, and a screw associated with the body of the shuttle adapted to pass through said last-mentioned aligning apertures for the purpose of fastening the box in the recess.

JAMES SHAW.
